Application July 21, 1950, Serial No. 11,293

Term of patent 14 years

(Cl. D44—15)

To all whom it may concern:

Be it known that I, R. Guy Cowan, a citizen of the United States, residing at Fayetteville, county of Onondaga, State of New York, have invented a new, original, and ornamental Design for a Cover for Sugar Bowl, of which the following is a specification, reference being had to the accompanying drawing, forming a part hereof.

Figure 1 is a top plan view of a cover for sugar bowl embodying my new design.

Figure 2 is a fragmentary sectional view taken on line 2—2 of Figure 1.

Figure 3 is a side elevational view.

Figure 4 is a fragmentary sectional view taken on line 4—4 of Figure 1.

The dominant feature of the design consists in the relatively broad and shallow, spiral-fluted, exterior paneling of the top surface of the cover terminating in and blending with a smooth, unfluted, marginal border surface, in combina-

tion with the spirally-grooved, center projection of the knob as shown.

I claim:

The ornamental design for a cover for sugar bowl, as shown and described.

R. GUY COWAN.
